CLAIM

The ornamental design for a track mounted fan unit, as shown and described.

DESCRIPTION

FIG. 1 is a front, top and right side perspective view of a track mounted fan unit showing my new design; FIG. 2 is a partial front elevational view thereof; FIG. 3 is a partial rear elevational view thereof; FIG. 4 is a partial bottom plan view thereof; FIG. 5 is a partial left side elevation view thereof; and, FIG. 6 is a top plan view thereof, the bottom view being a mirror image of the top view shown in FIG. 6. The track mounted fan unit has been broken away in FIGS. 2-6 for ease of illustration.

FIG. 1

FIG. 3

FIG. 2

FIG. 6

FIG. 4

FIG. 5
